(57) **CLAIM**

The ornamental design for an unmanned vertical takeoff and landing vehicle, as shown and described.

DESCRIPTION

FIG. 1 is a top, rear, left side perspective view of an unmanned vertical takeoff and landing vehicle showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom elevational view thereof.

The broken lines shown in the drawings depict portions of the unmanned vertical takeoff and landing vehicle that form no part of the claimed design.
